UNITED STATES PATENT OFFICE.

FREDERICK J. OSIUS, OF RACINE, WISCONSIN.

AGITATOR IMPLEMENT.

1,047,279.

Specification of Letters Patent. Patented Dec. 17, 1912.

Application filed April 10, 1911. Serial No. 620,258.

To all whom it may concern:

Be it known that I, FREDERICK J. OSIUS, a citizen of the United States, and resident of Racine, in the county of Racine and State 5 of Wisconsin, have invented certain new and useful Improvements in Agitator Implements; and I do hereby declare that the following is a full, clear, and exact description thereof.

- 10 My invention refers to portable electric driven mixing implements for liquid beverages or the like, its object being to provide structural features whereby the apparatus is rendered durable, simple, positive in its operation and efficient, and at the same time can be economically manufactured, the main 15 objects being: to provide efficient means for insulating the motor casing from its supporting bracket; to provide a peripherally notched agitator disk whereby efficiency in mixing is insured; to provide the hollow supporting post with drain openings intersecting its base, whereby accumulated moisture within the post is exhausted and thus 20 rust of the parts and the consequence is avoided; to provide metallic protecting jackets for the motor-brush insulating sleeves, the jackets being seated upon the external wall of the motor-housing through 25 which said sleeves project, whereby breakage or damage thereto incidental to an inadvertent blow is remedied; to provide the spring-controlled telescopic motor-supporting standard with a locking dog whereby 30 said standard and its attached agitating mechanism can be locked down to its working position; to provide an upwardly inclined tongue that is cut from the standard wall and adapted to engage the top edge of 35 the post whereby said telescopically united parts are prevented from being separated after they are once assembled, except through a positive operation whereby the tongue is 40 released through the insertion of a tool within a slot formed in the post; to provide 45 a simple spring-controlled plug for closing terminals of the electric motor circuit incidental to the apparatus being lowered to its working position, the plug being carried by a plunger that is under the control of a coiled spring having its ends abutting the 50 post base and head of the standard whereby said standard is lifted when relieved of pressure and the closing plug incidental to 55 this movement is automatically disengaged
- from the circuit closing terminals, which, in this instance, are shown as springs.
- With the above objects in view my invention consists in certain peculiarities of construction and combination of parts as are 60 hereinafter set forth with reference to the accompanying drawings and subsequently claimed.
- In the drawings Figure 1 represents an elevation of an implement embodying the 65 features of my invention with parts broken away and parts in section to more clearly illustrate the novel features; Fig. 2, an enlarged detail sectional view of the standard head showing the circuit-closing plug in engagement with the spring terminals, the section being indicated by line 2—2 of Fig. 1; Fig. 3, an enlarged sectional plan view, the section being indicated by line 3—3 of Fig. 1, said section illustrating in particular the 70 circular agitator disk provided with peripheral notches, and Fig. 4, a detail plan view of a portion of the motor-supporting bracket showing the motor attached to the arms of said bracket and the means of insulating the motor-attaching screws from the motor casing, the arms being broken away and in section at their ends to clearly illustrate this feature.
- Referring by characters to the drawings, 75 1 represents a metallic base that is suitably secured to a bed 1^a, the base having attached thereto a hollow post 2, into which is fitted a vertically adjustable hollow standard 3. The upper end of the standard has secured 80 thereto a hollow bracket having a hollow handle 4 extending therefrom, and a hollow neck portion 4^a in the opposite direction, from which neck spanner arms 5 extend. The bore of the neck 4^a has fitted thereto a 85 flanged sleeve 4^b, which sleeve extends outwardly from the neck and enters an aperture in the motor-housing 6, the said housing being also secured to the arms 5 by means of screws 5^a that pass through apertures in the 90 ends of the arms and are in threaded engagement with the housing, the screws being insulated from said arms by insulating thimbles 5^b and washers 5^c. Thus the aforesaid 95 housing, while connected at three points with the bracket, is entirely insulated therefrom so as to insure the operator against possible shock from the electric energy.
- Journaled in end bearings of the motor-housing is a motor-shaft 7 which carries the 100 105 110

usual commutator 7^a of an electric motor, which commutator is engaged by spring-controlled brushes 8 that are provided with insulating sleeves 9 which extend through apertures provided therefor in the housing. In order to protect these brittle insulating sleeves from breakage due to an accidental blow, the same are armored by metallic protecting jackets 10, which jackets fit tightly over the ends of the sleeves, being provided with flanges 10^a that abut the outer walls of the housing, whereby the impact of a blow will be resisted. The lower end of the motor-shaft extends through its journal and has secured thereto a stem 11 by means of a head 11^a that is brazed upon the end of the stem and held in engagement with the motor-shaft by a set-screw 12. The lower end of the stem is provided with a circular agitator disk 13 having its periphery notched at regular intervals thereabout whereby the liquid or other product to which the agitator is applied is thoroughly mixed owing to the irregular surfaces presented to the liquid, the same being revolved at a high speed. The neck 4^a of the bracket is provided with an aperture into which the head of the standard 3 is fitted, the same being secured by rivets 14 that pass through the bracket neck, standard head and ears of a cap 15, which cap is fitted over the bracket aperture as shown in Fig. 1. An insulated block 16 is secured to the head end of the hollow standard, which block is provided with a central aperture having a flared mouth, there being a pair of terminal springs 17 secured to the upper face of the block and extending through the central aperture therein for engagement with a plug 18, which is carried by a plunger 19 composed of insulating material, that is reciprocatively mounted within the hollow standard. A delicate coiled spring 20 is fitted over the plunger within the standard, its ends being interposed between the post base 1 and block 16 at the head of said standard, the said spring being secured to the plunger 19 by one or more contracted coils which engage a central annular recess in the plunger intermediate of its ends.

Conductor wires *a*, *b*, pass through the hollow handle, apertures in the head of the standard and hollow portion of the bracket and are connected to the brushes 8 as shown. The conductor wire *b* is interrupted within the neck of the bracket and its interrupted ends are secured to the terminal springs 17. Owing to the large diameter of the coiled spring 20 and the corresponding large diameter of the plunger 19, lateral movement of the spring within the standard can not be of such moment as to short circuit the motor current when the plug engages the terminal spring 17, the play of the plug and spring being so limited that, owing to the flare upon

the bottom of the terminal springs, said plunger is insured in its seat therebetween whereby the motor circuit is closed, which closure is effected by a depression of the standard in opposition to spring 19, and when the neck of the bracket has moved down to an engaging position with the mouth of the post, the bottom of the plunger will have engaged the base 1 of said post and thus just prior to engagement of the bracket neck and top of the post said plug will be positively forced into engagement with the terminal springs, the circuit being thus closed. In the meantime the agitator has been lowered within the contents of a vessel which is designed to be gripped by a vessel-clip 21 that is adjustably secured to said post.

The mouth of the post is provided with an engaging member 22 for a spring tongue 23, which tongue is formed by slitting the upper edge of a standard reinforcing ferrule 24, the tongue being thereafter pressed outwardly for engagement of the adjacent inner face of the post, it being understood that the ferrule is suitably secured to the bottom end of the standard and constitutes a guide therefor in connection with the post at this end, whereby lateral play is limited in the telescopic union between these parts. Thus it will be seen that after the standard has been inserted into the post the spring tongue 23 will prevent disengagement of the same from said post inadvertently, but should it be desired to dismantle these parts, it can be accomplished by first permitting the tongue 23 to engage the stop member 22 and thereafter a tool may be inserted through a slotted aperture 22^a in the post just below the stop member, whereby the tongue is pressed inwardly to clear said stop member. The post is provided with a series of apertures in its walls 2^a, which apertures are located just above the base-plate 1 and adapted to permit drainage of moisture or the like from the interior of the post, which moisture is liable to accumulate in an implement of this character wherein it is utilized in connection with mixing liquids.

The block 16 of insulated material is secured to the head of the standard 3 and neck portion of the bracket by means of set screws 25, 25^a, which set screws pass through the neck standard and engage the block therewithin. The screw 25^a is provided with an eared head 26 between which ears is mounted a locking dog 27, the same being fulcrumed upon a pin 27^a. When the standard is fully telescoped within the post the nose of this dog engages a flange 28 of the post and thus locks the standard down in its working position whereby the closed motor-circuit is constantly maintained until such time as the dog is released by the operator, which release is effected by pressing the 130

tail of the dog so as to clear its nose from engagement with the flange.

I claim:

1. In an agitator, the combination of a hollow post, a hollow supporting standard in telescopic union with the hollow post, a hollow handle bracket secured to the head of the standard, arms extending from the bracket, an electric motor secured to the 5 arms, an insulating block secured in the standard head, electric conductors for the motor extending through the hollow bracket and connecting the motor, terminals interrupting one of the conductors carried by the 10 block, a non-conducting plunger mounted in the standard having a circuit closing plug in its end, a coiled spring interposed between the base of the post and head of the standard, and means for securing the plunger and 15 spring together intermediate of the ends of the spring, the lower end of the plunger being adapted to abut the bottom of the post when the standard is depressed to effect closure of the circuit.
2. In an agitator, the combination of a motor-casing, alined journal bearings therein, a handle extending from the casing, an electric motor-shaft mounted in the casing 20 bearings, one end of which motor-shaft is adapted to protrude through the casing, and a circular disk secured to the protruding end of the shaft, the disk being provided with notched edges.
3. In an agitator, the combination of a 25 spring-controlled standard, a bracket secured to the head of the standard, a motor-housing carried by the bracket having apertures therein, a motor mounted in the housing, brushes for the motor, insulating sleeves 30 surrounding the motor brushes extending through the housing apertures, and metallic protecting jackets fitting over the protruding ends of the sleeves abutting said motor-housing.
4. In an agitator, the combination of a 35 hollow post, a spring-controlled standard mounted in the post, a motor carried by said standard, electric conductors for the motor,

terminals interrupting one of the conductors carried by the standard, a spring-controlled 50 supporting plug within the standard for engagement with the terminals whereby depression of the standard will effect a closure of the circuit, and a locking-dog carried by said standard engageable with the post when 55 the standard is depressed to effect closure of the motor circuit.

5. An agitator comprising a hollow standard, a motor-driven agitator carried thereby, a hollow supporting post fitted about the 60 standard, a catch member in connection with the mouth of the post, and a tongue projecting from the bottom portion of said standard for engagement with the catch member whereby inadvertent disengagement 65 of the post and standard is prevented, and means in connection with the post for permitting access to said tongue to effect disengagement of the standard therefrom.

6. An agitator comprising a base, a post 70 extending therefrom having drain apertures in its walls adjacent to the base, a spring-controlled standard in telescopic union with the post, and a motor-driven agitator carried by the standard.

7. An agitator comprising a spring-controlled standard, a bracket secured to the head of the standard having a hollow handle and hollow neck portion, arms extending from the neck portion having apertured 80 ends, an apertured motor-housing fitted between the arms, screws fitted through the arm apertures for securing the housing thereto, insulating thimbles interposed between the screws and arm apertures whereby 85 the housing is insulated therefrom, and an insulating sleeve extending from the bracket neck into an aperture of said housing.

In testimony that I claim the foregoing I have hereunto set my hand at Milwaukee in 90 the county of Milwaukee and State of Wisconsin in the presence of two witnesses.

FREDERICK J. OSIUS.
